UNITED STATES PATENT OFFICE

ARTHUR F. DONOVAN, OF HARTFORD, CONNECTICUT, ASSIGNOR TO COLT'S PATENT FIRE ARMS MANUFACTURING CO., OF HARTFORD, CONNECTICUT, A CORPORATION OF CONNECTICUT

DESIGN FOR A DRESS BUCKLE OR SIMILAR ARTICLE

Application filed October 5, 1932. Serial No. 45,221. Term of patent 7 years.

To all whom it may concern:

Be it known that I, ARTHUR F. DONOVAN, a citizen of the United States, residing at Hartford, in the county of Hartford and State of Connecticut, have invented a new, original, and ornamental Design for a Dress Buckle or Similar Article, of which the following is a specification, reference being had to the accompanying drawing.

Of the drawing:

Fig. 1 is a front view of a dress buckle or similar article embodying my invention.

Fig. 2 is a sectional view along the line 2—2 of Fig. 1.

Fig. 3 is an edge view.

I claim:

The ornamental design for a dress buckle or similar article as shown.

ARTHUR F. DONOVAN.
